LLP(57) **CLAIM**

The ornamental design for a radiation image conversion plate, as shown and described.

DESCRIPTION

FIG. 1 is a front view of a radiation image conversion plate of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a cross sectional view thereof, taken along line 8-8 of FIG. 1; and,

FIG. 9 is an enlarged cross sectional view thereof, taken along line 9-9 of FIG. 8.

The features shown in dotted lines depict environmental subject matter only and form no part of the claimed design.
